SAFETY BELT BUCKLE

Robert C. Fisher, 580 E. Long Lake Road,
Bloomfield Hills, Mich.

Filed May 28, 1964, Ser. No. 30,200

Term of patent 14 years

(Cl. D17—1)

FIG. 1 is a perspective view of a safety belt buckle showing my new design;

FIG. 2 is a side elevational view in inverted position;

FIG. 3 is a top plan view;

FIG. 4 is an elevational view taken from the left of FIG. 3;

FIG. 5 is an elevational view taken from the right of FIG. 3;

FIG. 6 is a side elevational view; and

FIG. 7 is a bottom plan view.

The essential features of my design reside in the portions shown in solid lines.

I claim:

The ornamental design for a safety belt buckle, as shown and described.
